UNITED STATES PATENT OFFICE.

ALY I. SCHALL, OF YONKERS, NEW YORK.

ANTIREFILLABLE BOTTLE.

1,217,509.

Specification of Letters Patent. Patented Feb. 27, 1917.

Application filed April 30, 1912. Serial No. 694,229.

To all whom it may concern:

Be it known that I, ALY I. SCHALL, a subject of the Emperor of Austria-Hungary, residing at Yonkers, in the county of West Chester and State of New York, have invented new and useful Improvements in Antirefillable Bottles, of which the following is a specification.

My invention relates to the class of non-refillable bottles, and more particularly to a bottle having a locking mechanism within its neck which prevents the refilling of the same, except when said mechanism is withdrawn by the use of a special tool.

15 The primary object of my invention is to provide a non-refillable bottle of simple yet efficient construction which shall have means whereby a cap may be locked to the top of said bottle, and not removed except through 20 the means aforesaid.

Another object of my invention is to provide a bottle of the foregoing type having a cap of such construction as to cause any liquid forced through one side of said cap to 25 flow out of the other without entering said bottle.

A still further object of my invention is to provide a bottle having the foregoing features which may be locked to the body of 30 said bottle in a new and novel manner.

With the foregoing and other objects in view, my invention consists in such details of construction and in the arrangement and combination of parts as will be hereinafter 35 more fully described and specifically pointed out in the appended claims.

In describing my invention in detail reference will be had to the accompanying drawings wherein like characters denote like 40 or corresponding parts throughout the several views, and in which—

Figure 1 is a vertical sectional view of a portion of a bottle incorporating my improvements.

45 Fig. 2 is a vertical sectional view of a detail, showing the locking means.

Fig. 3 is a horizontal sectional view taken on the line 3—3 of Fig. 2.

Fig. 4 is a detailed view looking down 50 upon the cap.

Fig. 5 is a detail sectional view of the under side of the cap taken on the line 5—5 of Fig. 1, and

Fig. 6 combines two detail views of the 55 special tool used for unlocking the mechanism of my bottle.

In reducing the invention to practice a bottle 1 of usual construction is employed. This bottle has the customary neck 2 which however is separated from the interior of the bottle by means of a bridge piece 3, through which pass apertures 4 and 5. In the neck 2 is also disposed a partition 6 cast integral with the remainder of the bottle, thus causing the aperture 5 to extend 60 in a long passage way 7 to the upper end of the said neck as will be readily understood. The remainder of the neck is entirely open as shown at 8, this space communicating 65 with the body through the aperture 4.

In the center of the bridge piece 3 is an aperture centrally disposed in the bridge piece and the upper face of the bridge being hollowed out as shown at 10 for a purpose which will be hereinafter more fully pointed 70 out. A plug 11, provided with a flared head, is passed upwardly through a centrally disposed aperture in the bridge 3, and may, if desired, be held in place by a seal 12, which may be either glass or other 75 suitable vitreous substance. Said plug 11 is provided with external screw threads 13, upon the shank, which are adapted to engage internal threads 14 disposed in the ends of the hollow connecting member 15. In 80 cases where the device of my invention is applied to common types of bottles which have openings in the bottom which are closed by cork and seals, especially where the bottles are not of the elongated but of 85 the squat type, it will be readily seen that the plug 11 could be readily inserted by a magnetized screw driver, or other suitable means, and thereafter sealed. Said hollow 90 connecting member is also internally screw threaded at its other end so as to receive the screw threaded end 16 of an elongated stem 17 disposed within the hollow space of the neck of the bottle. The screw threads on the member 16 and the corresponding 95 end of the member 15 must be opposite from the screw threads 13 and 14. In other words one set of threads must be right-hand threads while the other must be left-hand threads. It makes no difference as to the 100 relative position of the two sets of threads.

In the center of the tubular member 15 is disposed a cross or other irregularly shaped member 18, this being rigidly secured to the member 15 so that it may be 110 engaged by a tool in a manner hereinafter set forth, thus permitting the release of the

member 15 from the plug 11 and the withdrawal of the entire interior mechanism of my bottle.

The stem 17 referred to is hollow its entire length as illustrated at 19, the passage way designated by the last mentioned numeral opening through the top of a cap 20 as illustrated. The special tool 21 illustrated in Fig. 6 may be inserted through the cap 20 into the passage way 19 and engage the cross 18, thus permitting the member 15 to be turned or unscrewed from the plug 11 and withdrawn as before mentioned.

15 In order to secure a tight joint as well as a resilient one between the member 15 and the bridge piece 3 I insert between these members a washer 22 made of cork or other similar material.

20 Referring again to the cap 20 it is pointed out that said cap is rigidly connected to the tubular stem 17, and is entirely hollow except where the passage way 19 passes through said cap. The under face is provided with an aperture 23 conforming in size, shape and position with the end of the passage way 7 so that when said cap is in position any fluid passing through the passage way 7 will find its way into the hollow cap. Oppositely disposed openings 24 are formed in the edge of the cap 20 so as to permit the contents of said cap to escape.

The cap referred to as well as the stem 17 is also connected with the solid member 25 which is provided with the shoulder 26 disposed adjacent the shoulder 27 formed on the neck of the bottle, so that a cork or other washer 28 may be inserted between said shoulders thus forming a tight joint. An 40 opening 30 is provided through the portion 25 of the cap thereby forming an air vent so that the liquid may be poured from the bottle.

45 It will be seen that it is impossible to fill this bottle except by inserting the special tool provided for the purpose through the passage way 19 engaging the cross 18, and withdrawing the entire locking mechanism. Anyone not provided with such a tool will 50 find it impossible to refill the bottle without breaking the neck or at least the locking device thereof, which of course will be readily apparent and make it clear that fraudulent means have been resorted to in 55 order to refill said bottle. If it should be attempted to fill the bottle by forcing liquid through the apertures 24 into the cap 20, it will be found that the liquid merely flows out of said cap through the other aperture

24 and that none of it will find its way into 60 the bottle.

I desire it to be understood that the foregoing describes merely the preferred form of my invention and that slight changes in the construction and in the arrangement and 65 combination of the several parts may be resorted to without departing from the spirit of my invention provided such changes fall within the scope of the appended claims.

Having thus fully described my invention, 70 what I claim as new and desire to secure by Letters Patent, is:

1. In a device of the character described, a bottle having a neck provided with a bridge near the base thereof, said bridge 75 having apertures therein, said neck having a passage-way therethrough, a bottle cap on the end of said neck, said cap having an aperture registering with said passage-way, a depending stem connected to said cap and 80 having a passage-way extending therethrough, a stud having threads screwed into said bridge, a hollow connecting member internally threaded at each end, one end adapted to engage the threads on one end 85 of said stud and the other end adapted to engage screw threads on the end of said depending stem, one set of threads being right-handed and the other left-handed, and means in said connecting member adapted 90 to receive a special tool passed through said stem whereby the cap and connecting member may be taken from the bottle.

2. In a device of the character described, a bottle having a neck provided with a 95 bridge near the base thereof, said bridge having apertures therein, said neck having a passage-way therethrough, a bottle cap on the end of said neck, said cap having an aperture registering with said passage way, 100 a depending stem connected to said cap and having a passage-way extending therethrough, a stud having threads screwed into said bridge, a hollow connecting member internally threaded at each end, one end 105 adapted to engage the threads on one end of said stud and the other end adapted to engage screw threads on the end of said depending stem, one set of threads being right-handed and the other left-handed, means in 110 said connecting member adapted to receive a special tool passed through said slot whereby the cap and connecting member may be taken from the bottle.

ALY I. SCHALL.
